(57) **CLAIM**

We claim the ornamental design for a fencing assembly bracket, as shown and described.

DESCRIPTION

FIG. 1 is an elevation view of the rear of the fencing assembly bracket;

FIG. 2 is an elevation view of the front of the fencing assembly bracket;

FIG. 3 is an elevation view of the front of the fencing assembly bracket;

FIG. 4 is a rear view of the fencing assembly bracket;

FIG. 5 is a front view of the fencing assembly bracket;

FIG. 6 is a side view of the fencing assembly bracket;

FIG. 7 is a side view of the fencing assembly bracket;

FIG. 8 is a top view of the fencing assembly bracket; and,

FIG. 9 is a bottom view of the fencing assembly bracket. The broken lines depict portions of the fencing assembly bracket that form no part of the claim.
